APPARATUS FOR WASHING CLOTHES

Peter Eduard Geldhof, Syracuse, N. Y., assignor
to Easy Washing Machine Corporation, Syracuse, N. Y., a corporation of Delaware

Application January 25, 1935, Serial No. 3,423

18 Claims. (Cl. 68—133)

This invention relates to new and useful improvements in apparatus for washing clothes, and more particularly, to washing machines of the agitator type.

5 I have discovered that a more violent agitation of the clothes and a better cleansing action can be obtained by employing a new and distinctive mode of dolly operation. More specifically, it is an object of this invention to provide driving 10 means for actuating dollies in clothes washing machines which impart an oscillating movement to the clothes and washing fluid, and also a progressive circulatory movement in one direction around the washing machine vat, whereby more 15 complete circulation of the clothes is obtained.

A further object of the invention is to provide driving means for dollies of washing machines that imparts rotation of the dolly in alternate directions through unequal angular distances so as to produce, in addition to the oscillatory agitation of the clothes, a progressive step-by-step circulation in one direction, whereby the clothes are more violently agitated, and more completely exposed to the cleansing action of the fluid.

20 Although my invention is broadly applicable to dollies of the oscillating type, such as that shown in Geldhof Patent No. 1,937,884, I have found that when applied to the type of dolly construction disclosed in United States Patent No. 1,923,580, issued August 22, 1933, to J. C. Nelson, greatly 25 improved results can be obtained over those obtainable with ordinary dollies.

It is a further object of my invention to improve the washing efficiency of a spiral dolly of the type shown in the Nelson patent above referred to. I have discovered that this can be accomplished by increasing the velocity of circulation of the washing fluid and clothes in the advancing spiral direction and decreasing the velocity of the dolly in the reverse direction without changing the period of oscillation of the dolly. Thus, in the forward or advancing spiral direction, the dolly is made to travel through a greater angular distance than in the reverse direction of travel. The result is that the velocity of circulation of the clothes and the washing fluid will be greatly increased, thereby permitting a larger quantity of clothes to be washed more effectively in a shorter period of time.

50 Other objects and advantages of this invention will appear from the following description taken in connection with the accompanying drawings in which:

Figure 1 is a horizontal sectional view through 55 the tub of a washing machine showing a dolly

in plan therein, operated in accordance with my invention.

Figure 2 is a cross sectional view taken through line 2—2 of Figure 5, illustrating the dolly driving mechanism of my invention.

Figure 3 is a sectional view taken along line 3—3 of Figure 4.

Figure 4 is a sectional view taken along line 4—4 of Figure 2.

Figure 5 is a sectional view taken along line 10 5—5 of Figure 2.

Figure 6 diagrammatically illustrates the path of circulation of the clothes and washing fluid within the washing vat produced by actuating the dolly in accordance with one of the methods 15 of my invention.

Figure 7 diagrammatically illustrates the path of circulation of clothes and washing fluid for a modified method of dolly operation.

Figure 8 is a perspective view of another form 20 of dolly which may be used in my invention.

In the drawings, a washing machine vat or tub 8 preferably circular in horizontal cross section is provided with a removable cover 9 and the bottom of the tub 8 has an opening substantially 25 centrally located adapted to receive one end of an upstanding sleeve 10, which may be secured to the bottom of the tub in any well-known water-tight manner.

A dolly shaft 11 is positioned within sleeve 10 30 extending upwardly beyond the end of the sleeve terminating in a splined end portion adapted to engage a similar splined portion in the closed end of dolly 12 for supporting the dolly and for imparting to it oscillatory motion.

Dolly 12, as shown in Figures 1, 6 and 7, is of a spiral type specifically illustrated and described in United States Patent No. 1,923,580 above referred to, and comprises a preferably conical shaped hub 12' having a series of, in this instance, 40 three spirally arranged blades 13, 14 and 15 thereon. Although these blades may project a uniform distance from the surface of the cone-shaped hub throughout their length, it is preferable that they should gradually widen from 45 their upper to their lower portion. It is also desirable to incline the spirally arranged blades with respect to a line normal to the axis of or to the surface of the cone.

The angle of inclination may be uniform 50 throughout the length of the blade, but preferably, increases from the upper portion of the blade downwardly to the lower portion. Thus a pocket is formed by the blades on the side thereof inclined toward the surface of the cone, 55

which, for the purpose of this specification, will be called the forward side. Rotation of the dolly in the clockwise direction as viewed in Figure 1 will also be designated as the forward direction of rotation.

The lower end of shaft 11 extends below the surface of the tube 8 into gear case 16 and is preferably journaled in an end thrust bearing 17 including an anti-friction ball 18 upon which shaft 11 rests, and is adapted to oscillate.

The driving mechanism for oscillating dolly shaft 11 comprises an electric motor 19 mounted in any suitable manner upon a framework, not shown, underneath the washing tub. Motor 19 is coupled through flexible coupling 20 to drive shaft 21 extending into gear case 16 and upon which is fixedly secured a pinion 22. Pinion 22 is adapted to mesh with gear 23 fixedly secured to shaft 24 also journaled in suitable bearings within gear case 16. Shaft 24 may be provided with a worm 25 clutched in operative relation with sleeve 26 integrally formed with gear 23.

Worm 25 is adapted to mesh with a worm wheel 27 revolvably mounted on a stub shaft 28 socketed in a suitable boss in the lower side of gear case 16. A crank pin 29 is eccentrically positioned and fixedly secured to worm wheel 27. Connecting rod 30 having a stirrup-shaped end portion 31 is journaled to crank pin 29 by means of a bearing 32 provided in the enlarged end of portion 31.

Connecting rod 30 is provided with a longitudinal bore adapted to receive a shaft 33 extending into the enclosure of portion 31 and carrying thereon a beveled gear 34 secured by means of a set screw 35. Beveled gear 34 is adapted to mesh with a similar beveled gear 36, in this instance, mounted on the free end of crank pin 29 and retained in position by a set screw 37. To the other end of shaft 33 is secured by a set screw 39, a worm 38 having a relatively large number of threads. Shaft 33 preferably extends beyond worm 38 and is journaled in a traversing frame 40, which, in this instance, may be integrally formed with connecting rod 30. Traversing frame 40 is adapted to slide in a guide member 41 comprising spaced upper and lower guide plates 43 and 44 pivotally mounted on dolly shaft 11, as shown in Figures 2 and 5.

The inner surface of plate 43 is provided with a channel 45 while a similar channel 46 is provided in opposed relation to channel 45 in the lower plate 44, the two channels being adapted to slidably receive traversing frame 40. Secured to dolly shaft 11 as by means of a key or set screw, 55 and positioned between guide plates 43 and 44 is a worm wheel 42 adapted to mesh with worm 38.

The operation of the driving mechanism for oscillating dolly 12 is as follows: Motor 19 drives worm 25 through pinion gears 22 and 23. Worm wheel 27 in mesh with worm 25 will be rotated, in this instance, in a clockwise direction as viewed in Figure 2.

Crank pin 29 will revolve with worm wheel 27 and impart substantially longitudinal reciprocating movement to connecting rod 30, worm 38 and traversing frame 40. Traversing frame 40 being adapted to slide in channels 45 and 46, will always maintain worm 38 in mesh with worm wheel 42. Guide member 41 being pivotally mounted with respect to dolly shaft 11, will accommodate changes in the angular position of connecting rod 30 accompanying its reciprocating movement produced by the rotation of crank pin 29. Worm 38 functions as a rack to oscillate worm wheel 42, which oscillates dolly shaft 11. If worm 38

were fixed with respect to connecting rod 30 and traversing frame 40, and not permitted to rotate, it would impart uniform oscillatory motion to dolly shaft 11 or, in other words, dolly shaft 11 would be alternately rotated in opposite directions through equal angular distances. However, shaft 33 is adapted to be rotated by means of gear 34 in mesh with gear 36 fixed upon crank pin 29.

As worm wheel 27 and crank pin 29 are rotated uniformly in a clockwise direction, as viewed in Figure 2, shaft 33 and worm 38 will also be rotated at a uniform velocity. Worm 38 being in mesh with worm wheel 42 on dolly shaft 11 will impart a clockwise rotation of constant velocity to dolly 12, as viewed in Figure 1.

The velocity of rotation of dolly 12 produced by the rotation of worm 38 will be algebraically additive to the velocity of rotation of the dolly produced by the reciprocating rack action of worm gear 38 when the worm 38 is moving toward the right. The net velocity of the dolly in that given direction will be the sum of the two velocities. When the linear movement of the worm 38 is in such a direction as to impart motion in the reverse direction to dolly 12, that is towards the left, as viewed in Figure 2, the net velocity of the dolly will be the difference between the two velocities; that is, the velocity imparted by the linear movement of worm 38 and the velocity imparted by the rotational movement of worm 38. Since the period of oscillation is constant, being determined by the constant rotation of worm wheel 27, the dolly will rotate through a greater angular distance in the clockwise than in the counter-clockwise direction.

In practice, I have found it desirable to rotate the dolly in a forward or clockwise direction through an arc of substantially 190 degrees more or less. The rotation of the dolly in the reverse direction is preferably limited to an angular displacement of substantially 160 degrees more or less. This is diagrammatically shown in Figure 1.

Considering the forward edge of blade 13 as a starting point, when the dolly is at rest, and crank pin 29 is in the position shown in Figure 2, the dolly will have rotated in a clockwise direction through an arc of 190 degrees at the time when crank pin 29 reaches a position 180 degrees from the starting point. As crank pin 29 continues to rotate from the 180 degree position to the starting point, thereby imparting a reverse direction of rotation to dolly 12, the dolly will travel through an arc of only 160 degrees as shown in Figure 1. Upon the second revolution of crank pin 29, the cycle of operation is repeated in which the dolly, starting from its new position 30 degrees advanced from the former starting position, again advances 190 degrees, and then moves in a reverse direction only 160 degrees. Thus, it is seen that the dolly progressively, in the step-by-step manner, advances in a forward, or in this instance, a clockwise direction.

The increase in velocity of the dolly in the forward direction and the decrease in velocity of the dolly in the opposite direction, from that of a dolly of the Nelson type when oscillated with equal oscillations in both directions, greatly increases the velocity of the clothes and washing fluid in the forward direction.

The path of movement of the clothes and washing fluid is schematically illustrated in Figure 6. In accordance with the theory of operation fully described in the Nelson patent above referred to, the vacuum created between and adjacent the upper portions of the blades of the dolly upon

reverse movement thereof, draws the clothes down between the blades to be forced to the bottom of the vat and discharged outwardly from the lower portion of the blade from which point they slowly rise to the surface taking a spiral path around the vat as shown by the long arrows in Figure 6. Under normal load conditions, this spiral path may extend substantially throughout the entire circumference of the vat, or in other words, the clothes may make a complete revolution or more before being again sucked downwardly between adjacent blades.

By way of comparison, the path of clothes and washing fluid produced by the dolly oscillated through equal reverse arcs in accordance with the Nelson Patent No. 1,923,580 under normal load conditions, is shown by the short arrows of Figure 6. The short arrows are used to designate a lower velocity than that obtained by employing the method of this invention. By increasing the velocity of rotation of the dolly in the forward direction and securing a step-by-step progressive rotation of the dolly in the clockwise direction, it is possible to secure a high fluid velocity and a more rapid circulation and more thorough agitation of the clothes. It is, therefore, apparent that a greater amount of clothes may be more thoroughly cleansed in a shorter period of time.

The operation as formerly described was for a condition in which worm gear 27 was rotated in the clockwise direction. Now, if worm gear 27 is driven in a counter-clockwise direction, beveled gear 36 will also drive shaft 33 through gear 34 in a reverse direction. Reversing the direction of rotation of shaft 33 and, consequently, worm 38, will, due to the rotation of worm gear 38 alone, apart from its reciprocatory movement, impart a uniform rotation of dolly 12 in a counter-clockwise direction when viewed as shown in Figure 1. The reciprocating movement of worm 38 will remain unaffected. The net result upon the action of the dolly 12 will be the reverse of that formerly described. In this instance, the velocity of the dolly in a forward direction will be equal to the difference of the velocity imparted to it by the linear movement of worm 38 and the velocity imparted to it by the rotational movement of worm 38. The velocity of dolly 12 in the counter-clockwise direction will be the sum of the aforementioned velocities. The dolly will be rotated in a clockwise direction through 160 degrees, and in a counter-clockwise direction through 190 degrees, the result being that the dolly progressively travels step-by-step in a counter-clockwise direction. The effect of this particular movement is to decrease the forward rotational velocity of the clothes and washing fluid caused by the inclination and curvature of the blades, but at the same time, due to the increased velocity of the dolly in the opposite direction, a greater vacuum is created between and adjacent the upper portions of the blades so that the clothes, piece by piece, are more violently drawn down between adjacent blades and are more forcefully ejected from the lower portions.

The path of movement of the clothes and washing fluid is diagrammatically illustrated in Figure 7. It will be noted that this path has been greatly shortened and the circulation has been reduced considerably circumferentially around the vat as compared to the action of dolly and washing fluid shown in Figure 6 however the vertical component of the velocity has been greatly increased.

Although the path of movement of the clothes

circumferentially around the vat has been materially decreased, the velocity of the clothes inwardly toward the center of the dolly and then downwardly and outwardly toward the sides of the vat has been materially increased.

From the foregoing description, it will be apparent that the forward rotational velocity of the dolly may be decreased to such an extent accompanied by a commensurate increase in the velocity of the dolly in a reverse direction as to completely neutralize the normal forward circulation of clothes and washing fluid caused by the curvature and inclination of the blades, or, if desired, by still further increasing the velocity of rotation of the dolly in the counter-clockwise direction the contents of the vat may be caused to flow in the counter-clockwise direction.

My invention may be applied with good results to any of the commercial forms of dolly now in use, for example to a dolly of the type shown in Geldhof Patent No. 1,937,884 as illustrated in Fig. 8. This type of dolly has a plurality of diametrically extending plane blades 48 with intermediate smaller blades 49 arranged circumferentially about an upstanding central hub. When a dolly of this type is rotated alternately in opposite directions through equal angular distances, the clothes are subjected to a limited oscillatory circumferential movement within the vat as well as to a movement upward and down therein. The washing efficiency of dollies of this general type may be improved by increasing the velocity of the dolly in one direction and decreasing the velocity of the dolly in the opposite direction so that the dolly travels through a greater angular distance in one direction than in the opposite direction, in accordance with this invention. Thus, the clothes are subjected to a more violent agitation and, at the same time, are more completely circulated through the washing fluid in that they are actually made to progress in a step-by-step manner circumferentially around the vat. Inasmuch as the dolly shown in the said Geldhof patent is symmetrical, the washing action would be the same for a progression of the clothes and washing fluid in either direction around the vat.

Although I have shown and described specific forms and constructions of apparatus as constituting embodiments of the invention, I do not desire to limit myself to the details of the constructions and forms illustrated, as various changes and modifications may be made without departing from the spirit and scope of the appended claims.

I claim:

1. In a machine for washing clothes wherein an agitator is mounted in a vat containing clothes and washing fluid, a plurality of blades mounted on the agitator, said blades extending from said agitator in a manner such that when the agitator is oscillated through equal angles in each direction of rotation of the agitator the clothes are oscillated backwardly and forwardly through equal angles in accordance with the oscillations of the agitator, driving mechanism for the agitator, said agitator being oscillated by said mechanism at all times in the same horizontal plane, and means in connection with the driving mechanism for oscillating the agitator through a larger angle in one direction of rotation than in the other whereby the agitator rotates step by step in one direction and the clothes and washing fluid are circulated in one resultant circulatory direction around the vat.

2. In a machine for washing clothes having a

clothes washing element of the submerged type mounted in a vat containing the clothes and washing fluid, the bottom of said clothes washing element being approximately half the diameter of the vat, said clothes washing element having a plurality of blades extending therefrom, driving mechanism for the clothes washing element including a shaft extending upward through the bottom of the vat and operatively connected to the clothes washing element, said clothes washing element being oscillated by said driving mechanism at all times in the same horizontal plane, and means in connection with the driving mechanism for oscillating the clothes washing element through a larger angle in one direction of rotation than in the other direction, whereby the clothes washing element rotates step by step in one direction.

3. In a machine for washing clothes, a vat, an upstanding oscillatable agitator mounted therein, driving mechanism for oscillating said agitator, said agitator being oscillated by said driving mechanism at all times in the same horizontal plane, said agitator including means configurated so as to circulate fluid and clothes around the vat in one general circulatory direction responsive to the operation of the agitator, and means in the driving mechanism for imparting a smaller angle of rotation to said agitator in the general direction of circulation of the clothes and fluid than in the opposite direction.

4. In a machine for washing clothes, a vat, an upstanding oscillatable agitator mounted therein, driving mechanism for oscillating said agitator, said agitator being oscillated by said driving mechanism at all times in the same horizontal plane, said agitator including means configurated so as to circulate fluid and clothes around the vat in one general circulatory direction responsive to the operation of the agitator, and means in the driving mechanism for imparting a greater angle of rotation to said agitator in one direction than in the opposite direction.

5. In a machine for washing clothes, a vat, an upstanding oscillatable agitator mounted therein, driving mechanism for oscillating said agitator, said agitator being oscillated by said driving mechanism at all times in the same horizontal plane, said agitator including means configurated so as to circulate fluid and clothes around the vat in one general circulatory direction responsive to the operation of the agitator, and means in the driving mechanism for imparting a greater angle of rotation to said agitator in the general direction of circulation of the clothes and fluid than in the opposite direction.

6. In a machine for washing clothes, a vat, an upstanding oscillatable agitator mounted therein, driving mechanism for oscillating said agitator, said agitator being oscillated by said driving mechanism at all times in the same horizontal plane, said agitator including means configurated so as to circulate fluid and clothes around the vat in one general circulatory direction responsive to the operation of the agitator, and means in the driving mechanism for imparting a higher average rotational velocity to said agitator in the general direction of circulation of clothes and fluid than in the opposite direction.

7. In a machine for washing clothes, a vat, an upstanding oscillatable agitator mounted therein, driving mechanism for oscillating said agitator, said agitator being oscillated by said driving mechanism at all times in the same hori-

zontal plane, said agitator including means configurated so as to circulate fluid and clothes around the vat in one general circulatory direction responsive to the operation of the agitator, and means in the driving mechanism for imparting a lower average rotational velocity to said agitator in the general direction of circulation of clothes and fluid than in the opposite direction.

8. In a differential driving-gear, a support, a shaft rotatably mounted thereon, a drive-gear wheel revolvably mounted in the support, a planetary bevel-gear-wheel rigidly united to one side of said drive-wheel and spaced eccentrically thereof, a crank-pin mounted in said drive-wheel concentric with the bevel-gear-wheel, a link member having one end pivoted upon the crank-pin and its opposite end forming a sleeve, a connecting-rod revolvably mounted in said sleeve and extending outwardly at both ends thereof and carrying a bevel-gear-pinion upon one end adapted to mesh with the bevel-gear-wheel and having its opposite end formed into a worm, a worm-gear-wheel mounted upon the lower end of the shaft in mesh with the worm on the connecting-rod, a sleeve having a lateral extension pivoted upon the shaft and adapted to guide and hold the worm in mesh with the worm-gear-wheel, and means for actuating the drive-gear-wheel.

9. In a differential driving-gear, supporting means, a pair of shafts rotatably mounted thereon, a drive-gear united to the first of said shafts, a planetary bevel-gear-wheel rigidly united to said drive-wheel and spaced eccentrically thereof, a crank-pin mounted in said drive-wheel concentric with the bevel-gear-wheel, a link member having one end pivoted upon the crank-pin and its opposite end forming a sleeve, a connecting-rod revolvably mounted in said sleeve and extending outwardly at both ends thereof and carrying a bevel-gear-pinion upon one end adapted to mesh with the bevel-gear-wheel and having its opposite end formed into a worm, a worm-gear-wheel mounted upon the corresponding part of the second shaft in mesh with the worm on the connecting-rod, a sleeve having a lateral extension pivoted upon the second shaft and adapted to guide and hold the worm in mesh with the worm-gear-wheel, and means for actuating the drive-gear-wheel.

10. In a differential driving-gear, supporting means, a vertical shaft rotatably mounted therein, a connecting-rod having one end formed into a worm, a worm-gear-wheel mounted upon the lower end of the shaft in mesh with the worm on the connecting-rod, a sleeve having a lateral extension pivoted upon the shaft and adapted to guide and hold the worm in mesh with the worm-gear-wheel, and means for continuously rotating the connecting-rod in one direction in a single horizontal plane and for driving it reciprocatingly longitudinally in the same plane.

11. In a differential driving-gear, supporting means, a shaft rotatably mounted therein, a connecting-rod having one end formed into a worm, a worm-gear-wheel mounted upon the lower end of the shaft in mesh with the worm on the connecting-rod, a sleeve having a lateral extension pivoted upon the shaft and adapted to guide and hold the worm in mesh with the worm-gear-wheel, and unitary means for continuously rotating the connecting-rod in one direction in a single plane at a right angle to the shaft and for driving it reciprocatingly longitudinally in the same plane.

12. In a differential driving-gear, supporting

means, a pair of shafts rotatably mounted thereon, a drive-gear united to one end of the first of said shafts, a planetary bevel-gear-wheel rigidly united to said drive-wheel and spaced eccentrically thereof, a crank-pin mounted in said drive-wheel concentric with the bevel-gear-wheel, a link member having one end pivoted upon the crank-pin and its opposite end forming a sleeve, a connecting-rod revolvably mounted in said sleeve and extending outwardly at both ends thereof and carrying a bevel-gear-pinion upon one end adapted to mesh with the bevel-gear-wheel and having its opposite end formed into a worm, and means united to the second shaft whereby the rotary and reciprocating motion of the connecting-rod when driven by the bevel-gears and crank-pin, may be transmitted to the second shaft and cause a reciprocating rotary movement thereof and also a progressive rotational movement with each reciprocation thereof.

13. In a differential driving-gear for a shaft, the combination with a housing, of a shaft carrying a worm-gear-wheel mounted in said housing, a sleeve having an extension formed thereon pivotally mounted upon said shaft, a connecting-rod having a worm formed upon one end thereof and slidably and rotatably mounted in said sleeve, in mesh with the gear-wheel, and means for simultaneously reciprocating and rotating said connecting-rod in a single plane at a right angle to the shaft.

14. Means for securing a differential reciprocating rotary action of a shaft which consists in securing a worm-gear to such shaft and securing a worm in mesh with such worm-gear, in combination with means for simultaneously reciprocating longitudinally and rotating the worm in a single plane at a right angle to the shaft.

15. Means for simultaneously reciprocating and rotating a worm which consists in forming said worm upon a connecting-rod and subjecting it to reciprocating action by a crank and crank-pin

suitably coupled to the connecting-rod, and rotat-
ing the connecting-rod by the rotation of a bevel-
pinion secured upon such rod in mesh with a
planetary bevel-gear mounted adjacent to and
concentric with the crank-pin.

16. In a mechanical movement, horizontal drive and driven gear-wheels, means by which the drive wheel may cause a simultaneous reciprocatory rotary and a progressive rotary movement of the driven wheel comprising a rotatable connecting-rod having one end pivotally linked to a crank-pin carried by the drive-wheel and carrying a bevel-pinion meshed with a bevel-gear-wheel rigidly united to the drive wheel concentric with crank-pin, and carrying on its other end a worm mesh- 15
ing with the driven wheel.

17. In a mechanical movement, drive and driven gear-wheels mounted in the same plane, means by which the drive wheel may cause a simultaneous reciprocatory rotary and a progressive rotary movement of the driven wheel comprising a rotatable connecting-rod having one end pivotally linked to a crank-pin carried by the drive wheel and carrying a bevel-pinion meshed with a bevel-gear-wheel rigidly united to the drive 25
wheel concentric with crank-pin, and carrying on its other end a worm meshing with the driven wheel.

18. In a mechanical movement, a support, a drive and driven gear-wheels mounted thereon and spaced apart, and means by which the drive wheel may cause a simultaneous reciprocatory rotary and a progressive rotary movement of the driven wheel comprising a rotatable connecting-rod having one end pivotally linked to a crank-pin 35
carried by the drive wheel and carrying a bevel-pinion meshed with a bevel-gear-wheel rigidly united to the drive wheel concentric with crank-pin, and carrying on its other end a worm mesh- 40
ing with the driven wheel.

P. EDUARD GELDHOF.
